UNITED STATES PATENT OFFICE.

ORRELL ASHTON, DECEASED, LATE OF SWAMPSCOTT, MASSACHUSETTS, BY HANNAH ASHTON, EXECUTRIX, OF SWAMPSCOTT, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

TACKING MECHANISM.

1,279,491.

Specification of Letters Patent. Patented Sept. 24, 1918.

Original application filed January 21, 1914, Serial No. 813,571. Divided and this application filed February 15, 1916. Serial No. 78,522.

To all whom it may concern:

Be it known that ORRELL ASHTON, late of Swampscott, in the county of Essex and State of Massachusetts, deceased, invented 5 certain Improvements in Tacking Mechanisms, of which the following description, in connection with the accompanying drawings, is a specification, like reference characters on the drawings indicating like parts 10 in the several figures.

This invention relates to tacking mechanisms and particularly to such mechanisms as are adapted for driving a plurality of tacks adjacent to the edge of a shoe bottom 15 or other article, this application being a division of my prior application, Ser. No. 813,571, filed Jan. 21, 1914 covering improvements in pulling-over and lasting machines.

20 A feature of this invention consists in a novel organization of tacker mechanism constructed and arranged to permit a plurality of tacks to be driven at uniform or predetermined distances from the edges of different shoes. The construction herein shown, by way of example, comprises a plurality of adjacent tackers connected to a common carrier, the carrier and at least one of the 25 tackers being relatively movable, combined with means to engage the side of the shoe or other article and position the tackers relatively in response to such engagement for driving the tacks at predetermined relative distances from edges of varying contours. 30 An advantage of this construction is that by its use a plurality of tacks can be driven in the bottom of a shoe at the same distance from its edge unaffected by the curvature of the edge. Another feature of this 35 invention consists in novel mechanism for operating the drivers of relatively movable tackers whatever may be the position of the tackers relatively to one another. The use of such mechanism renders possible an 40 economy of parts in a multiple tack driving mechanism. Another feature of the invention consists in a construction and arrangement of tack holders adapting them for advantageous use in a multiple tack driving 45 mechanism as well as in a single tack driving mechanism. These and other features

of the invention will now be described with the aid of the accompanying drawings which show an illustrative embodiment of the invention, and the invention will then be 55 pointed out in the claims.

Figure 1 of the drawings is a perspective view of a multiple tack driving mechanism embodying this invention.

Fig. 2 is a perspective view of said mechanism from another angle.

Fig. 3 shows one of the tack holders separated from the other.

The invention is herein shown for the purpose of explanation as embodied in the 65 side tacker mechanism of the pulling-over machine illustrated in my said earlier application. That mechanism comprises a carrier 2 between which and the shoe 3 relative movement is made to take place for 70 positioning the tack holders over the edge of the shoe bottom. The illustrated mechanism includes four tackers, the first, second and fourth of which, counting from the left in Fig. 1, are pivoted at 5 to the carrier 2 75 while the third tacker is rigid with said carrier. Each of the tackers is equipped with an adjustable abutment piece 6 arranged, in the illustrative construction shown, to engage the side of the shoe for determining the 80 extent to which each tacker shall extend over the shoe bottom and thereby determining the distance at which each tacker shall insert its tack from the immediately adjacent portion of the shoe edge. The first, second, and 85 fourth tackers are each held pressed yielding forward by a spring 8 mounted on a fixed part of the carrier 2, being limited in this movement by the engagement of walls of slots 9 with stop screws 10 which are 90 rigid with the carrier 2. As the shoe is pressed laterally against the abutments 6 or, in the machine of said application, as the carrier 2 is yieldingly advanced toward the shoe, the abutments 6 on the yieldingly 95 mounted tackers engage the side of the shoe directly opposite the points where the respective tackers will insert their tacks and cause said tackers to arrange themselves according to the curvature of the shoe edge. 100 As the advance continues the movement of the carrier and the rigid tacker is arrested

by the work, the abutment 6 on this tacker, in the construction shown, being arranged to contact directly with the shoe. The tackers are then located to insert their tacks 5 each at the distance from the edge of the shoe predetermined by the adjustment of its abutment 6, and these relative distances are independent of the contour of the shoe edge, being the same, for example, for a shoe having a sharply curved edge as for a shoe 10 having a straight edge.

Each of the tackers has an independent driver rod 12 the lower portion of which is guided in the mid-plate 14 of the tacker. 15 The upper end of the rod for the third tacker is secured to the driver bar 15, but the upper ends of the other rods are provided with hooked blocks 16 constituting a pivotal connection with a cross-head 17 of 20 the driver bar 15. This fork and pin connection of the driver rods to the driver bar permits the rods for the first, second and fourth tackers to move out and in independently of each other and relatively to the 25 driver bar as the tackers adjust themselves relatively for inserting each tack at the predetermined distance from the edge of the shoe for which the abutments on the individual tackers are set.

30 The tacker holder comprises, for each tacker, parallel and closely adjacent horizontal plates 20 pivotally connected by cross plates 21 at their outer ends and pressed together by a spring 22. The plates of each 35 pair are shaped on the adjacent faces of their inner end portions to present a tack pocket in alignment with the driver rod 12 of that tacker. The plates 20 are formed to fit snugly the neck of the mid plate 14 which 40 is grooved to provide upper and lower shoulders between which the plates 20 are supported, and the springs 22 are strong enough to retain the holder securely in place during use, while permitting removal by the 45 operator, for any purpose whatever, by spreading the front ends of the plates and pulling them off backwardly without the use of any tools.

The operation of the improved tacking 50 mechanism has been sufficiently explained in connection with the description of the mechanism. It will be understood that the tacks may be supplied and the driver bar may be operated by any suitable means.

55 Having explained the nature of the invention and described one embodiment thereof, I claim as new and desire to secure by Letters Patent of the United States:—

1. A shoe tacking mechanism having, in 60 combination, a plurality of adjacent tackers, a unitary carrier for the several tackers to move said tackers across the shoe edge, one of the tackers being movably connected to the carrier, and stop devices on said tackers 65 to engage the shoe and position the tackers

relatively for driving the tacks at predetermined relative distances from shoe edges of varying contour.

2. A shoe tacking mechanism having, in combination, a plurality of adjacent tackers, 70 a carrier to move said tackers across the shoe edge, a relatively rigid connection between said carrier and one of the tackers, a relatively yielding connection between another of the tackers and said carrier, and 75 stop devices on said tackers to engage the shoe edge and position the tackers relatively for driving the tacks at predetermined relative distances from shoe edges of varying contour, the stop device on the rigidly connected tacker limiting the movement of the 80 carrier over the shoe.

3. A shoe tacking mechanism having, in combination, a plurality of adjacent tackers, 85 a carrier to move said tackers across the shoe edge, connections permitting one tacker to move on its carrier relatively to another, means for positioning said tackers relatively according to the contour of the adjacent portion of the edge of the last, a 90 driver bar in said carrier, driver rods in said tackers, and a fork and pin connection between the bar and the rods, the arrangement being such that the bar can operate the rods in all operative positions of the 95 tackers.

4. A shoe tacking mechanism having, in combination, a tacker carrier, a plurality of tackers movable across the shoe edge to inserting position, abutments for the side of 100 the shoe depending from said tackers, one of said tackers having a substantially rigid connection with the carrier and the others having a yielding connection therewith and being capable of taking positions relatively 105 thereto in accordance with the edge contour of the shoe, and means for driving tacks from the tackers in their adjusted positions.

5. A shoe tacking mechanism having, in combination, a tacker carrier, a plurality of 110 tackers movably connected therewith and adapted to position themselves relatively in accordance with the contour of the work in a series extending lengthwise of an edge of 115 the work, each tacker comprising a tack holder and a driver rod, a driver bar, a transverse head on the lower end of the bar arranged to extend lengthwise of the edge of the work, and hooks formed on the driver rods to enable said rods to move transversely 120 of the edge of the work while maintaining operative connection with the transverse head of the bar.

6. A shoe tacking mechanism having, in combination, a tacker carrier, a plurality of 125 tackers relatively movable thereon and adapted to be positioned relatively in accordance with the edge contour of the work, each tacker comprising a tack holder and a driver rod, and a driver bar rigidly 130

5 nected with one of said driver rods and having a loose connection with another one to maintain operative relation with a plurality of driver rods in the different relative positions which they occupy at different times.

10 7. A shoe tacking mechanism having, in combination, a tacker carrier, tackers pivotally supported thereon, springs yieldingly pressing said tackers forwardly, abutments on the tackers for engaging the sides of the shoe to position the tackers relatively as allowed by the springs, a driver bar operating in the carrier and having a laterally extended head piece, and tack driver rods having a connection with the head piece, the arrangement being such that the tackers are permitted the forward and backward relative movement required.

15 20 8. A shoe tacking mechanism having, in combination, a tacker carrier and a tacker comprising a tack driver and a supporting member grooved on its lateral sides to provide supporting ledges, tack holding plates having a tack pocket between their front ends and pivotally connected at their rear ends for separating movement of their front ends, said plates resting upon said ledges, and a spring holding the plates normally together, substantially as described.

25 30 35 40 9. In a shoe tacking mechanism, a tacker comprising a tack driver, a member in which the driver is guided, tack holding plates embracing said member and provided at their front ends with a tack pocket under the driver, and a spring holding the plates in embracing relation with said member and permitting them to be sprung apart at their front ends and to be pulled off backwardly from said member.

45 50 10. In a shoe tacking mechanism, a tack driving bar mounted for tacker positioning movement relatively to the work and also for tack driving movement, a plurality of tackers independently movable forwardly and backwardly relatively to one another and to said bar for adaptation to the contour of the work, tack driving rods, and operative connections between said bar and rods for permitting operation of the driving rods by the driver bar in varying angular relations of the rods to the bar.

55 60 65 11. In a shoe tacking mechanism, a tacker carrier or support, a tack driving bar movable therein, a plurality of tackers one of which is pivotally mounted on the carrier for movement relatively to another tacker, a tack driving rod for each tacker, and operative connections between said bar and rods constructed and arranged to permit lateral bodily movement of a rod relatively to the bar as the pivoted tacker assumes different positions.

12. A shoe tacking mechanism having, in combination, a tacker support, and a plural-

ity of tackers mounted on said support, one of the tackers being fixed to the support and another yieldably connected to the support to permit relative movement of said support and yieldably connected tacker transversely of the edge of the shoe.

70 75 80 85 13. A shoe tacking mechanism having, in combination, a tacker support, a plurality of tackers mounted on said support, one of said tackers being fixed to the support and having means to engage the side of the shoe to determine the position of said support in relation to the shoe for the tack driving operation, another of said tackers being pivoted to the support for movement relatively to said fixed tacker toward or from the side of the shoe, and yielding means for normally positioning said pivoted tacker in advance of said fixed tacker in the direction of the side of the shoe.

90 95 14. A shoe tacking mechanism having, in combination, a plurality of adjacent tackers, a carrier for moving said tackers transversely of the shoe edge to tack driving position, the tackers being relatively movable on the carrier in directions toward or from the side of the shoe, and means constructed and arranged for engagement with the shoe upon a movement of the carrier toward the shoe to cause the tackers to assume positions for driving their tacks at predetermined distances from the shoe edge irrespective of the contour of the shoe.

100 105 15. In a shoe tacking mechanism, a tack driver, a support having means for guiding the driver in its operative movement, a pair of plates embracing said support and coöperating to position a tack in alinement with the driver, and spring means for pressing said plates toward each other to position them detachably upon said support.

110 115 16. In a shoe tacking mechanism, a tack driver, a supporting member, a pair of plates embracing said member and having recesses coöperating to provide a tack pocket, the supporting member being constructed to position the plates in operative relation to the driver, and spring means for pressing the plates toward each other to hold them detachably on the supporting member with said recesses in position to hold a tack.

120 125 17. A shoe tacking mechanism having, in combination, a tacker support movable transversely of the edge of a shoe, a plurality of tackers mounted on said support and independently movable forwardly and backwardly relatively to one another to adapt them to the contour of the shoe, driver rods for the several tackers, and operating means for said rods relatively to which the rods are movable with the tackers, said operating means being constructed to maintain operative connection with the several rods in all positions of the tackers.

130 18. A shoe tacking mechanism having, in

- combination, a tacker support, a plurality of tackers mounted on said support for relative swinging movement in planes transverse to the edge of the work to position themselves 5 in accordance with the contour of the work, driver rods for the several tackers, and operating means for said rods constructed to maintain operative connection with the rods in different adjusted positions of the tackers.
- 10 19. A shoe tacking mechanism having, in combination, a tacker support, a plurality of tackers mounted on said support, one of the tackers being fixed to the support and another of the tackers being movably connected to the support, and a stop device on one of said tackers to position said tacker by engagement with the work.
- 20 20. A shoe tacking mechanism having, in combination, a tacker carrier, a tacker fixed 25 on the carrier, another tacker yieldingly connected to the carrier, said carrier being movable to carry the tackers across the edge of a shoe, and a stop device for determining the operative position of one of the tackers by engagement with the shoe.
- 30 21. A shoe tacking mechanism having, in combination, a tacker support mounted for tacker positioning movement relatively to the work, a plurality of tackers independently mounted on said support for positioning movement relatively to one another in the general direction of said movement of the support, means for determining the operative position of one of the tackers by engagement with the work, tack drivers for the several tackers, and means for operating said drivers in unison.
- 40 22. A shoe tacking mechanism having, in combination, a tacker support movable 45 transversely of the edge of a shoe, a plurality of tackers independently mounted on said support with provision for relative yielding movement between different tackers in directions transverse to the edge of the shoe to position the tackers relatively to the shoe, tack drivers for the several tackers, and means for operating said drivers in unison.
- 50 23. A shoe tacking mechanism having, in combination, a tacker support, a plurality of tackers independently mounted on said support with provision for relative movement of different tackers in directions transverse to the edge of a shoe, tack drivers for the several tackers, means for operating said drivers in unison, means for effecting a relative positioning movement of said support and the shoe, and means comprising abutments carried by the different tackers for
- 60 causing the tackers to assume a definite relation to one another in said relative positioning movement of the support and the shoe.
- 65 24. A shoe tacking mechanism having, in combination, a tacker support movable transversely of the edge of a shoe, a tacker fixed to said support, means for limiting movement of said support toward tack driving position, another tacker mounted on said support with provision for movement relatively to said fixed tacker in directions transverse to the edge of the shoe, yielding means for normally positioning said movable tacker in an advanced relation to the fixed tacker, drivers for said tackers, means for 70 operating said drivers in unison, and means comprising an abutment on said movable tacker to cause it to be positioned relatively to the shoe and to the fixed tacker as the support moves toward tack driving position.
- 75 25. A shoe tacking mechanism having, in combination, a tacker support, a plurality of tackers mounted on said support, one of the tackers being substantially rigid with the support against movement in a direction transverse to the edge of a shoe, means for determining the relative positions of said support and the shoe to cause said rigidly mounted tacker to be positioned for driving 80 its tack at a predetermined distance from the edge of the shoe, another of said tackers being mounted on the support with provision for relative movement of said tacker and support in a direction transverse to the edge 85 of the shoe, and means for causing said last named tacker to position itself relatively to the rigid tacker upon a relative positioning movement of the tacker support and the shoe.
- 90 26. A shoe tacking mechanism having, in combination, a tacker support, a plurality of tackers mounted on said support with provision for relative movement of different tackers in directions transverse to the edge 95 of a shoe, driver rods for the several tackers, and a driver bar for operating said rods, said bar being substantially rigid with one of said rods against movement transverse to the edge of the shoe and having a connection 100 with another of said rods constructed to permit relative movement of the bar and said last named rod transversely of the edge of the shoe.
- 105 In testimony whereof I have signed my 110 name to this specification.
- HANNAH ASHTON,
Executrix of the will of Orrell Ashton.
